US0D1006943S

(12) **United States Design Patent** (10) **Patent No.:** **US D1,006,943 S**
Peng (45) **Date of Patent:** **** Dec. 5, 2023**

(54) **SQUIRREL BAFFLE**

(71) Applicant: **SHENZHEN HUAYUN TECHNOLOGY CO., LTD**, Shenzhen (CN)

(72) Inventor: **Longji Peng**, Shenzhen (CN)

(**) Term: **15 Years**

(21) Appl. No.: **29/791,542**

(22) Filed: **Jan. 17, 2022**

(51) **LOC (14) Cl.** **22-06**

(52) **U.S. Cl.**

USPC **D22/119**; D22/120

(58) **Field of Classification Search**

USPC D22/119-120; D30/124, 151, 199; 52/83, 101

CPC A01K 39/00; A01K 39/0113

(57) **CLAIM**

The ornamental design for a squirrel baffle, as shown and described.

DESCRIPTION

FIG. 1 is a perspective view of a squirrel baffle showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.
